UNITED STATES PATENT OFFICE.

ERNEST S. ROE, OF PLYMOUTH, MICHIGAN, ASSIGNOR TO THE MARKHAM AIR RIFLE CO., OF PLYMOUTH, MICHIGAN, A CORPORATION OF MICHIGAN.

POP-GUN.

1,293,933.

Specification of Letters Patent. Patented Feb. 11, 1919.

Application filed February 16, 1918. Serial No. 217,535.

To all whom it may concern:

Be it known that I, ERNEST S. ROE, a citizen of the United States of America, residing at Plymouth, in the county of Wayne 5 and State of Michigan, have invented certain new and useful Improvements in Pop-Guns, of which the following is a specification, reference being had therein to the accompanying drawings.

10 The invention relates to pop guns of that type having a reciprocable handle member and one of the objects of the invention is to obtain a construction in which the gun can be fired when the handle member is moving 15 in either direction and in which the projectile is retained within the barrel of the gun. Another object is to obtain a construction in which the gun is fired and loaded when the handle member is moving in either direction. 20 A further object is to obtain a construction in which the means for loading the gun also retains the handle member adjacent to the barrel. Still further objects reside in the novel arrangements and combinations of 25 parts as more fully hereinafter set forth.

In the drawings:

Figure 1 is a side elevation of the pop gun;

Fig. 2 is a longitudinal sectional view 30 thereof;

Fig. 3 is a transverse sectional view on the line 3—3 of Fig. 2;

Fig. 4 is a sectional side elevation of a modified construction;

35 Fig. 5 is a transverse sectional view on the line 5—5 of Fig. 4;

Figs. 6 and 7 are side elevations of details.

A is the barrel of the gun, B the stock, C the false trigger, C' the trigger mechanism 40 casing and D the handle member reciprocable longitudinally of the barrel. E and E' are the cylinders secured within the barrel and spaced from each other, and F and F' the projectiles, preferably corks, adapted to engage respectively in the adjacent ends of the cylinders E and E'. G and G' are pistons slidably engaging the cylinders E and E' respectively for ejecting the corks F and F' by compressing the air in the 45 cylinders between the corks and pistons. H is the loader intermediate the corks F and F' adapted to force the same into engagement with their respective cylinders.

For the purpose of actuating the pistons 50 and the loader the reciprocable handle mem-

ber D is secured thereto. The pistons G and G' have the U-shaped rods I and J respectively, each having one arm of the U extend axially of the cylinder and the other arm of the U extend adjacent to the barrel A to the end of the handle member D and then bend downwardly and enter the handle member at K, to which it is secured by the rivet L. The under side of the barrel A is provided with the slots M for the passage of the base 60 of the U. As shown, the rod J extends into the trigger mechanism casing C'. The loader H extends through the slot N in the under side of the barrel A and is secured to the handle member D by the base flange H' 65 outside of and adjacent to the barrel.

For the purpose of securing the handle member adjacent to the barrel, the loader H has the neck portion O slidably engaging the slot N and also has the enlarged circular 70 portion P having the shoulders P' slidably engage the barrel A adjacent to the slot N. With this arrangement the loader H is also a tie member between the barrel and handle member.

The corks F and F' are tapered so that as they wear they can be forced farther into their respective cylinders to obtain a tight fit. In order to limit the reciprocating movement of the handle member D in either 80 direction after the corks have become worn to prevent the injury to the gun, the ends N' of the slot N are located in advance of the ends of the cylinders E and E' so that the loader H will contact with the ends of the 85 slot in its reciprocations and cannot force the corks farther into engagement with the cylinders or contact with the cylinders to injure the same.

In operation, assuming the parts to be in 90 the position shown in Fig. 2, upon movement of the handle member D toward the right, the piston will compress the air within the cylinder E which will finally eject the cork F making a loud report in so doing. The loader H will meanwhile contact with the cork F' and force the same into firm engagement with the end of the cylinder E'. Upon moving the handle member 100 D in the reverse direction or to the left, the cork F' will be ejected making a loud report and the cork F forced into firm engagement with the end of the cylinder E. The loader H ties the handle member D to the barrel A 105 so that the handle member can not become 110

disengaged during its reciprocatory movements. After the corks have become worn, the loader H contacts with the ends of the slot N which limits the movements of the handle member D and prevents injury to the gun mechanism.

In the modified construction shown in Fig. 4 the pop gun has the same arrangement of parts as shown in Fig. 2 with the exception of the handle member and its connections to the loader and pistons. As shown, the handle member Q has the annular groove Q' in its periphery for engagement with the arms R of the bifurcated portion R' of the loader S. Fig. 6 shows the arms R of the loader as substantially parallel to each other before engagement in the groove Q' of the handle member, which are adapted to be bent inwardly at their outer ends after engagement, as shown by the dotted lines, so that they will lie within the groove. The handle member Q also has the longitudinal groove or channel Q² in its upper surface for engagement with the arms T of the U-shaped rods T' connected to the pistons. These arms extend adjacent to the lower side of the barrel and overlap each other within the groove or channel Q², their upper sides being substantially flush with the periphery of the handle member. The arms T are notched in their upper edges at U for engagement with the base of the bifurcated portion R' of the loader S, which will hold the same from disengagement from the handle member.

From the above description of the modified construction it will be readily seen that the loader is adapted to load the gun, ties the handle member to the barrel of the gun and also secures the rods connected to the pistons to the handle member. This construction is simple and presents a neat appearance.

What I claim as my invention is:

- 45 1. In a pop gun, the combination with the barrel of a pair of spaced pistons longitudinally slidably engaging said barrel, a loader within said barrel intermediate said pistons, and a handle member reciprocable longitudinally of said barrel and connected to said pistons and loader.
- 50 2. In a pop gun, the combination with the barrel of a pair of spaced pistons longitudinally slidably engaging said barrel, a loader within said barrel intermediate said pistons, a handle member reciprocable longitudinally of said barrel and connected to said pistons and loader, and means for limiting the reciprocatory movement of said handle member.
- 55 3. In a pop gun, the combination with the barrel of a pair of spaced pistons longitudinally slidably engaging said barrel, a loader within said barrel intermediate said pistons, and a handle member reciprocable

longitudinally of said barrel and connected to said pistons and loader, said barrel having a longitudinally-extending slot therein through which said loader passes, the ends of said slot limiting the reciprocatory movement of said handle member.

4. In a pop gun, the combination with the barrel of a pair of spaced cylinders therewithin, pistons longitudinally slidably engaging said cylinders, a loader within said barrel intermediate said cylinders, and a handle member reciprocable longitudinally of said barrel and connected to said pistons and loader, said barrel having a longitudinal slot in its underside engageable by said loader, the ends of said slot being located in advance of said cylinders.

5. In a pop gun, the combination with the barrel of a handle member reciprocable longitudinally thereof, spaced pistons movable in said barrel, U-shaped rods connecting said pistons and handle member, the arms of the U outside said barrel extending adjacent thereto, and a loader intermediate said pistons and connected to said handle member.

6. In a pop gun, the combination with the barrel, of a pair of cylinders therewithin, pistons within said cylinders, a loader within said barrel intermediate said cylinders and means for relatively moving said pistons and loader with respect to said cylinders.

7. In a pop gun, the combination with the barrel, of a piston therewithin, a handle member, a rod between said piston and handle member, and a loader within said gun tying said handle member to said barrel, and said rod to said handle member.

8. In a pop gun, the combination with the barrel having a pair of spaced cylinders formed therein, of projectiles engageable with said cylinders, a handle member reciprocable longitudinally thereof, means for alternatively forcing said projectiles into engagement with their respective cylinders, means for alternatively ejecting said projectiles from their respective cylinders, connections between said first-mentioned means and handle member, and other connections separate from said first-mentioned connections and between said second-mentioned means and handle member.

9. In a pop gun, the combination with the barrel, of a reciprocable handle member, means for loading said gun, means for firing said gun, connections between said loading means and handle member, and other connections separate from said first-mentioned connections and between said firing means and handle member.

10. In a pop gun, the combination with the barrel, of a reciprocable handle member, means for loading said gun, means for firing said gun, connections between said

loading means and handle member, and other connections between said firing means and handle member, said last-mentioned connections being secured to said handle member by said first-mentioned connections.

11. In a pop gun, the combination with the barrel, of a reciprocable handle member, a pair of spaced pistons within said barrel, a loader within said barrel intermediate said pistons, **U**-shaped rods connect-

ing said pistons and handle member, the arms of the **U** outside said barrel extending adjacent thereto and into said handle member and having transverse slots therethrough in alinement with each other, and complementary arms upon said loader and engaging said handle member and said alined slots in the arms of the **U**-shaped rods. 15

In testimony whereof I affix my signature.
ERNEST S. ROE.
